TOY PRINTING PRESS

Eugene Levay, New York, N. Y.

Application April 21, 1937, Serial No. 138,175

9 Claims. (Cl. 101—269)

The present invention relates to printing presses and more particularly to small hand presses, commonly regarded as toys. Among the objects of this invention are the provision of 5 a structure of the nature indicated which will be relatively inexpensive to manufacture; to provide a structure of the character indicated which may be used by children in the setting up and printing of cards and small notices; to provide 10 an instrumentality of the nature indicated with which children may set up type and produce printed matter without the investment of a large amount of money; to provide a structure in the nature of a toy which will still have practical 15 educational value in that it will assist in teaching children a trade; and such further objects, advantages, and capabilities as will hereafter appear and as are inherent in the construction disclosed herein. My invention further resides in 20 the combination, construction, and arrangement of parts illustrated in the accompanying drawings and, while I have shown therein what is now regarded as the preferred embodiment of this invention, I desire the same to be understood 25 as illustrative only and not to be interpreted in a limiting sense.

In the drawings annexed hereto and forming a part hereof,

Fig. 1 represents a side elevation of a structure 30 embodying my present invention;

Fig. 2 represents a front elevation of the structure shown in Fig. 1;

Fig. 3 represents a fragmentary section of a pivot joint connecting two parts of the structure shown in Figs. 1 and 2;

Fig. 4 represents a plan view of this structure in open position, as shown in Fig. 1;

Fig. 5 represents a plan view of this structure in closed position and with the paper-impressing roller over the chase;

Fig. 6 represents a fragmentary transverse sectional elevation taken substantially along the plane indicated by the line 6—6, Fig. 5; and

Fig. 7 represents a transverse sectional elevation taken substantially along the plane indicated by the line 7—7, Fig. 5.

Reference will now be made in greater detail to the annexed drawings for a more complete description of this invention. A body 1 is mounted on a base 2 and is provided, in its back side, with an opening to receive a drawer 3 having an end closure plate, bent over, as shown in Fig. 1, to form a finger-piece 4 by which the drawer can be pulled out of the body 1. This drawer is for 55 the reception of type, tools, and other equipment

needed in the operation of the press. At the back upper corners of the body are standards or brackets 5 upon which the frame 6 is pivotally mounted.

The frame 6 comprises the side pieces 7 and the apertured and flanged plate 8 to which the arms 7 are secured. Pivots 9 connect the arms 7 and the brackets 5, pivotally, and sleeves 10 surround the pivots or rivets 9 and space the arms 7 from the brackets 5. In this way, the 10 arms 7 are held spaced far enough from the sides of the body 1 to permit a pivotal motion with relation thereto. A generally U-shaped wire or rod 11, provided with a grip 12, is mounted in the flanges of the plate 8, as shown in Figs. 1 15 and 2, and is slidable therein for a purpose to be now disclosed.

On the arms of the U-shaped member 11 are mounted blocks 13 which are adjustable with relation to the arms and may be secured in 20 position, relatively thereto, by means of set screws 14. When the blocks have been properly adjusted with relation to the arms and the set screws have been tightened up, reciprocation of the arms will cause the blocks 13 to reciprocate 25 also. Mounted in openings in these blocks 13 is a shaft 15 which may rotate in the apertures in the blocks. On the shaft 15 is mounted a roller 17, the function of which is to press the paper into close engagement with the type mounted in the chase 18. In Figs. 4 and 5, the rectangle 19 represents an assemblage of type set up in the chase 18 and held in place therein by screws 20 which take the place of the quoins customarily used for this purpose. A spring 21 is 35 secured to the chase in any suitable manner, as by means of a screw 22. As is customary, the chase and type rest upon a bed, indicated in Figs. 1 and 2 by the numeral 23.

Links 24, shown most clearly in Fig. 1, are 40 pivotally connected to the arms 7 by pivots 9a, substantially identical with the pivots shown in Fig. 3. Pivot members 25 pass through the links 24 and axially through flanged wheels 26 which ride on tracks 27 along the sides of the press. The flanges 28 run along side the tracks 27 which serve as guides therefor. Between the links 24 and the heads of the pivot members 25 are attaching ears 29 to which are connected 45 ends of springs 30. The second ends of these 50 springs are connected at 31 to the base 2.

The other ends of the pivot members 25 are hollow and serve as bearings for a shaft 32 on which is mounted an inking roller 33. The body 1 is provided with a curved surface 34 which 55

carries the ink by means of which the roller 33 is inked as it rides over this surface. A table 35 is formed at approximately the lower limit of travel of the inking roller 33. When the handle comprising the members 11 and 12 is raised, the frame 6 is caused to turn about its pivots 9 to force the inking roller 33 across the type and down over the inking surface 34 where it picks up a fresh supply of ink. At the same time, the 5 spring 30 is stretched and holds the roller tightly against the inking surface. Also, when the handle is moved in the opposite direction, the links 24 are pulled backwardly and the inking roller 33 is moved across the type in the opposite direction, transferring ink to the type faces. During this movement, the spring 30 holds the 10 roller down against the type to cause close engagement of the two.

The sheets of paper to be printed are carried 20 by the frame 6 and held in place thereon by the springs 36. When the frame 6 is lowered to bring a sheet of paper into printing position, the inking roller is carried across the type, as explained above, and the paper comes down into position 25 over the type. Now, when the handle 11, 12 is pulled outwardly, the roller 17, above the sheet of paper, presses the latter into tight engagement with the type and the ink is transferred to the paper. The wheels 26 and tracks 27 hold 30 the inking roller up out of engagement with the chase, when the latter is not filled with type, but permit it to engage the type for the transference of ink thereto. When a sheet has been printed, it is removed from its position between the 35 frame 6 and the springs 36, and a new sheet is placed therein for the next impression. It is possible, if desired, to have several sheets carried by the paper-carrier at a time but it is considered better practice to insert a single sheet 40 and print this sheet before inserting the next sheet.

It is of course understood that the specific description of structure set forth above may be departed from without departing from the spirit 45 of my invention as set forth in this specification and the appended claims.

Having now described my invention, I claim:

1. A structure for the purpose indicated comprising a body having a compartment therein for 50 the reception and holding of a chase, a type-carrying chase receivable in said compartment to be held in substantially fixed position during use, a frame pivotally connected to said body to hold sheets of paper and carry same into a position immediately above said type, and a roller carried by said frame and movable longitudinally thereof to press said paper into contact with said type.

2. A structure for the purpose indicated comprising a body member having a roller-inking surface, a frame pivotally connected to said body, an inking roller carried by said frame and actuated thereby to be rolled over said inking surface as the frame is turned about its pivotal connection with the body, a type-carrying chase mounted in said body in the path of movement of said inking roller to hold the printing type in position to be inked by said roller, means connected 60 with said frame to hold paper and carry same into a position adjacent the chase so that ink on any type in the chase may be transferred to the paper, and other means carried by the frame for pressing the paper into engagement with the type, the means for pressing the paper against the type comprising a roller movable longitudinally of the frame in a position to engage the paper and press same against the type.

3. A structure as defined by claim 2 in which the means for pressing the paper into engagement with the type comprises a handle slidable in the frame, longitudinally thereof, and a roller carried by the handle and movable therewith longitudinally of the frame and over the paper to press same against the type. 5

4. In a printing press, a body having a chase receiving receptacle therein, a chase to be inserted in said receptacle, said chase having on 10 at least one edge a spring for holding the chase in position in the receptacle, said chase having means projecting from the opposite edge thereof and entering openings in a wall of said receptacle to assist in holding the chase in position in the 15 receptacle, and an inking roller rollable over the type held in the chase and spring-actuated into close engagement with said type.

5. In a printing press, in combination, a body, a frame pivotally carried thereby and provided 20 with means for holding one or more sheets of paper in a position to be carried into printing position, said frame being provided with aligned openings extending in a direction longitudinally of the frame, a U-shaped handle extending 25 through said openings and slidable therein, and a roller carried by said handle and movable therewith to be rolled over the paper to press it into engagement with the type.

6. A printing press comprising a body provided 30 at one end with an approximately cylindrical surface for the reception of ink to be applied to an inking roller, a frame pivotally connected to said body and provided adjacent one end with holding means for sheets of paper and having 35 links connected to its opposite end portion, a type-inking roller connected to said links and connected thereby to said pivoted frame, and means for forcing said inking roller against said approximately cylindrical surface to cause the 40 transfer of ink from the surface to the surface of the roller.

7. In a printing press having a body portion, a paper-carrying frame pivotally connected to the body portion, a roller-carrying unit slidably 45 carried by said frame, and a roller carried by said unit and supported in a position to be rolled over said paper and exert pressure against the same.

8. A structure for the purpose indicated comprising a body member having a roller-inking surface, a frame pivotally connected to said body, an inking roller carried by said frame and actuated thereby to be rolled over said inking surface as the frame is turned about its pivotal connection with the body, a type-carrying chase mounted 50 in said body in the path of movement of said inking roller to hold the printing type in position to be inked by said roller, means connected with said frame to hold paper and carry same 60 into a position adjacent the chase so that ink on any type in the chase may be transferred to the paper, and other means carried by the frame for pressing the paper into engagement with the type, the means for pressing the paper against the type comprising a roller movable longitudinally of the frame in a position to engage the paper and press same against the type. 65

9. In a structure for the purpose indicated, the combination of a body having a curved inking surface adjacent one end thereof, an inking roller rollable over said inking surface, springs for pressing said roller against said inking surface, a type receptacle located in said body in the path 70

of movement of said inking roller, means for moving said inking roller across the inking surface and the type-receptacle to cause transfer of ink from said inking surface to any type located within the type-receptacle, and a frame pivotally connected to said body and having paper-holding means thereon to carry paper to

the type upon pivotal movement of the frame, the opposite end of the frame being connected by the first mentioned means to the inking roller to cause the above described movement of the roller across the inking surface and the type. 5

EUGENE LEVAY.
